UNITED STATES PATENT OFFICE.

DAVID SWOPE, OF MERCHANTVILLE, NEW JERSEY.

CLAMP.

No. 823,903.

Specification of Letters Patent.

Patented June 19, 1906.

Application filed April 24, 1905. Serial No. 257,279.

To all whom it may concern:

Be it known that I, DAVID SWOPE, a citizen of the United States, residing in Merchantville, in the county of Camden, State of New Jersey, have invented a new and useful Clamp, of which the following is a specification.

My invention relates to the novel construction of clamp intended principally for gripping hides, skins, or other material during the act of stretching the same.

It is adapted to replace toggles which perforate, thus avoiding perforation of the hides for the insertion of the toggle-strings connecting to the frames.

The object of this invention is to produce a strong light compact structure of simple form which will retain the leather during treatment, so that the leather-finishing devices will not touch the jaws of the clamp.

A further object is to produce a structure not easily injured in use and one having a skeleton frame whereby a minimum surface of said frame is exposed to the enamel applied to the leather.

A further object is to produce a clamp which will tighten in use and which will retain any thickness of material.

Further objects will be apparent from the description and claims.

In the drawings, Figure 1 is a perspective view of one embodiment of my invention in open position. Fig. 2 is a longitudinal section of a clamp embodying my invention in operative position. Fig. 3 is a fragmentary side elevation of a structure embodying my invention. Fig. 4 is a longitudinal section of a portion of a clamp embodying my invention, showing the material as being gripped in a different manner.

Similar numerals indicate corresponding parts in the several views.

1 designates a clamp composed of two members 2 and 3, which are shown and preferably used in pivoted relation. Member 2, as shown, is composed of a single sheet or plate, whose middle front piece or portion 4 is rearwardly bent or turned at 5 to form a clamp or jaw 6. Upon each end of the middle front portion 4 is a rearwardly-extending arm 7. These two arms are curved in the form shown in the plane of the plate from which the arms 7 are formed, and they converge at the rear and are united by transverse overlapping extensions 8 and 9. It will be evident that this member 2 therefore

consists of a front piece or portion 4, having a rearwardly-extending clamping portion 6 and side walls 7, extending from the front portion 4 into juxtaposition at the rear. It 60 will be apparent that in my preferred construction, as seen in Fig. 1, the member 2 is hollow and that no bottom member is necessary.

The transverse rear extensions 8 and 9 of 65 the side arms 7 are most desirably shown in the illustration provided with substantially registering eyes 10 and 11, through which a conductor, rod, cord, or wire 19 may be passed. These eyes form guides for the rod, 70 wire, or conductor, while at the same time this conductor keeps the transverse extensions in position with the eyes substantially in line.

Within the hollow frame member 2 I place 75 member 3, preferably pivoted therein at 12 and 13, respectively, by extensions 14 and 15, which pass through the apertures 12 and 13. The internal member 3 comprises a front piece 16, the upper edge 20 of which contacts with the middle front portion 4 of the member 2, the material to be gripped being held between the upper face of the front piece 16 and the rearwardly-extending jaw 6, as shown in Fig. 2, although it will be apparent that, if desired, as shown in Fig. 4, the material 21 to be gripped may be so engaged by the clamp that it will be held between the middle front portion 4 of the member 2 and the upper edge 20 of the jaw 90 16 and between the rearward jaw 6 and the upper edge 20 of the front piece 16 of the internal member 3. Upon the opposite side of the pivot-point from the jaw 16 I form 85 an arm or extension 17, which I have 95 illustrated as lying at an angle to the jaw 16. It will be evident that this extension 17 has full play within the member 2, except as it may be restricted by engagement of the front piece or jaw 16 with the middle portion 100 4 of the member 2 or with the material grasped between these parts.

At any suitable point in the extension 17 I form an aperture 18, through which the cord, wire, or other flexible or stiff material or connector 19, passing through apertures or eyes 10 and 11, is also adapted to pass. This cord or other connector, flexible or rigid, which I will hereinafter call a "connector," without, however, any intention of restricting it to flexible material, may terminate immediately beyond the aperture 18 in a head

or enlargement or in other means by which it is prevented from being drawn through said aperture, or it may be connected in such manner that strain upon the connector upon 5 that portion beyond the eyes 10 and 11, if the connector terminate at aperture 18, or upon either or both ends of the connector in case the end does not occur at 18, will draw the extension 17 toward the inner portion of the 10 member 2, moving the front piece 16 into its gripping position. It will be evident that in case of such use increase of strain causes increase of gripping action. It will be further evident that the tendency of the clamping 15 portion is to place itself, with the eyes, below the upper surface of the rearward jaw 6, as seen by Fig. 2, in which the line of direction of the leather is above the rear of the clamp, and, in fact, with the whole rear portion of 20 the clamp substantially below this level. (Shown in dotted line at $\alpha\alpha$ in Fig. 2.) This line represents the plane of the material stretched. The aperture through the transverse extensions 8 and 9 is in a plane above 25 the pivotal point of the internal clamping member. It will be apparent from Fig. 2 that the laterally-extending sides 7 of the hollow member 2 are bent upwardly at their rear, so that the aperture through the transverse extensions 8 and 9 are in a plane above 30 the pivotal point of the internal clamping member 3.

Having now described the nature and objects of the invention, what I claim as new, 35 and desire to secure by Letters Patent, is—

1. A clamp consisting of two members, one member comprising a front piece having a rearwardly-extending jaw, and having side pieces connected with said front piece and 40 rearwardly extending to come into proximity at their rear ends, and a second member comprising a front piece pivoted to said first member and provided with an arm extending rearwardly therefrom and angularly 45 thereto, said arm and the rear ends of said side pieces being apertured, and movable toward each other to cause the clamping.

2. In a device of the character described, a hollow apertured member having a front 50 piece and an upper rearwardly-extending jaw thereon, and an internal member pivoted within said hollow member and having a clamping-jaw, the upper edge of which, when in clamped position, engages said front piece beneath said upper rearwardly-extending jaw, whereby the material is clamped between the clamping-jaw of the internal member and the front piece and rearwardly-extending jaw of the hollow member, and 55 60 means engaging said internal member and passing through said aperture for clamping said members.

3. In a device of the character described, a hollow member having a rearwardly-extending jaw and a rear aperture, and an internal member pivoted to said hollow member and having a clamping-jaw and an arm rearwardly deflected therefrom, the end of said arm terminating within said hollow member, and means engaging said aperture for moving the jaws toward each other to clamp them. 65 70

4. In a device of the character described, a hollow member comprising a front piece, rearwardly-extending side arms overlapping each other at their rear, and a rearwardly-extending jaw at the upper end of said front piece, an internal clamping member pivoted to the rearwardly-extending arms of said hollow member in proximity to the front piece 75 thereof, said internal member comprising a clamping-jaw and an arm extending angularly therefrom, and means engaging said arm and passing through said hollow member to clamp the material between the clamping-jaw of the internal member and the front piece and rearwardly-extending jaw of said hollow member. 80 85

5. In a device of the character described, a hollow member having a rearwardly-extending jaw and rearwardly-extending side arms converging at their rear and united by transverse overlapping extensions, said extensions having an aperture therethrough, and an internal pivoted member comprising a 90 clamping-jaw, and an arm extending therefrom, said arm having an aperture therein, and a connector in connection with the aperture of said internal clamping member and passing through the aperture in the transverse overlapping extensions of said hollow member. 95 100

6. In a device of the character described, a hollow member having a rearwardly-extending jaw, rearwardly-extending side arms converging at their rear end and united by transverse overlapping extensions, said extensions having an aperture therethrough, and an internal pivoted member comprising a clamping-jaw, and an arm extending therefrom, 105 110 and a connector secured to said internal member and passing through the aperture in the transverse overlapping extensions of said hollow member, the rearwardly-extending portions of said hollow member being bent upwardly at their rear so that the aperture through said transverse extensions is in a plane above the pivotal point of said internal clamping member. 115
